US0D1104807S

(12) **United States Design Patent** (10) **Patent No.:** **US D1,104,807 S**
(45) **Date of Patent:** **** Dec. 9, 2025**

(54) **WEIGHING APPARATUS**

(71) Applicant: **Mettler-Toledo GmbH**, Greifensee (CH)

(72) Inventors: **Manfred Stefan Alexander Held**, Hamburg (DE); **Thilo Hogrebe**, Hamburg (DE); **Sandra Jasmin Ehrbar**, Volketswil (CH); **Xinghong Chen**, Shanghai (CN); **Heqiao Wang**, Shanghai (CN); **Mi Zhou**, Shanghai (CN); **Qinghua Xiong**, Shanghai (CN)

(73) Assignee: **Mettler-Toledo GmbH**, Greifensee (CH)

(**) Term: **15 Years**

(21) Appl. No.: **29/895,542**

(22) Filed: **Jun. 22, 2023**

(51) **LOC (15) Cl.** **10-04**

(52) **U.S. Cl.** **D10/91**
USPC **D10/91**

CLAIM

The ornamental design for a weighing apparatus, as shown and described.

DESCRIPTION

FIG. 1 is a perspective view of a weighing apparatus of our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the figures are for the purpose of illustrating the weighing apparatus and form no part of the claimed design.

1 Claim, 6 Drawing Sheets
